(57) **CLAIM**

The ornamental design for a device for applying nail decals, as shown and described.

DESCRIPTION

FIG. 1 is a top plan view of a device for applying nail decals showing my new design.

FIG. 2 is a bottom plan view thereof.

FIG. 3 is a front side elevation view thereof.

FIG. 4 is a right side elevation view thereof.

FIG. 5 is a top plan view of the second embodiment of the device shown in FIG. 1.

FIG. 6 is a bottom plan view thereof.

FIG. 7 is a front side elevation view thereof.

FIG. 8 is a right side elevation view thereof.

FIG. 9 is a top plan view of the third embodiment of the device shown in FIG. 1.

FIG. 10 is a bottom plan view thereof.

FIG. 11 is a front side elevation view thereof.

FIG. 12 is a right side elevation view thereof.

FIG. 13 is a top plan view of the fourth embodiment of the device shown in FIG. 1.

FIG. 14 is a bottom plan view thereof.

FIG. 15 is a front side elevation view thereof; and,

FIG. 16 is a right side elevation view thereof.

The dashed lines showing decals, perforations and additional tab portions are for illustrative purposes only and form no part of the claimed design. The separation and bracket are used to portray devices of varying lengths, wherein the appearance of any portion of the device between the break lines forms no part of the claimed design.
